UNITED STATES PATENT OFFICE.

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA.

METHOD OF DELIVERING FOLDED SHEETS.

1,266,741.

Specification of Letters Patent.

Patented May 21, 1918.

Original application filed June 16, 1913, Serial No. 773,918. Divided and this application filed December 3, 1917. Serial No. 205,136.

To all whom it may concern:

Be it known that I, HENRY A. WISE WOOD, a citizen of the United States, residing at New York, in the county of New York and 5 State of New York, have invented a new and useful Method of Delivering Folded Sheets, of which the following is a specification.

This is a division of my application for 10 patent on apparatus for delivering folded sheets filed June 16, 1913, Serial No. 773,918.

This invention relates to the delivery of folded sheets from the folding mechanism of a web printing press.

The principal object of the invention is to 15 provide for delivering the sheets in such a way that the uniform delivery of the sheets without longitudinal buckling or crumpling will be assured; and the speed of delivery can be materially increased.

20 For the purpose of securing this result the paper as it comes from the folding rolls is given a curve at the end of such a nature that longitudinal buckling is prevented and that when the front end strikes the fan 25 blade it will be capable of springing or yielding to prevent both longitudinal and lateral buckling of the front end.

Reference is to be had to the accompanying drawings, in which—

30 Figure 1 is an elevation of a fan delivery for carrying out this invention, and

Fig. 2 is a similar view showing the parts in other positions.

The mechanism is shown as arranged for 35 taking folded bundles of sheets from a pair of folding rolls 10. Instead of the usual straight paper guide a guide 11 is mounted on a stationary support 12 and provided with an upper concave curvature at 11^a, and 40 a lower convex curvature 11^b on the operative side thus being of an ogee or S shape. The usual rotary fan 12^a having curved blades 13 is provided. This is located in such position that as the blades swing over 45 into place for receiving the advance end of the bundle of sheets they cross the line of the guide at a point near that at which the curvature changes from concave to convex. The usual stop 14 is provided mounted on a 50 support 15 on the frame and the papers are delivered to delivery belts 16 or the like.

The method of delivery is as follows: The folded sheets coming down through the rolls 10 with the folded end forward strike the

concave surface 11^a. Thus they are given 55 a continuous transverse curve at the end uniform all the way across the bundle. As the bundle of sheets drops down the guide 11 this end curvature is maintained until the end of the bundle of sheets strikes a fan 60 blade. The formation of this curvature is indicated in the position A of Fig. 1 while the next result of it is indicated in position B in Fig. 2. In this latter position the curved bundle of sheets is just passing from 65 the concave to the convex portion of the guide. The curvature of the sheets at the end is maintained until the sheets strike the fan blade 13 which then just comes into proper position to receive the sheets. The 70 result at this point is important. With the bundle of sheets arranged in a plane, the sudden striking of the end thereof against the fan blade would have a tendency to buckle the sheets longitudinally at a point 75 near the advance end, and ordinarily there is no way of controlling this. But on account of the preliminary curve which has been given the bundle of sheets and which is maintained as described herein, this curved 80 end is unsupported at both edges when it strikes the fan blade. This causes the fan blade immediately to turn this advanced end reversely all the way across as indicated by the arrow in Fig. 2. In this way longitudinal crumpling is eliminated and all the 85 bundles of sheets are effected in the same way and a uniform product is secured. It is to be understood, of course, that the fan blades rotate more slowly than the speed of 90 the bundle of sheets down the guide, as is usually the case. Thus the speed of the sheets is retarded by the fan blade at the same time that the curvature is changed. By this method also it will be seen that the 95 blades of the fan take the bundle of sheets along the convex surface of the guide throughout the remainder of the travel thereof with the blades. Two other positions of the bundle are shown at C and D in 100 Figs. 1 and 2 respectively. At the bottom the bundles strike the stops in the usual way and the sheets are deposited on the delivery belts.

Although I have illustrated and described 105 only one way of carrying out the invention, I am aware of the fact that many modifications can be made therein by any person

skilled in the art without departing from the scope of the invention as expressed in the claims. Therefore, I do not wish to be limited in these respects, but what I do claim is:

1. The method of delivering folded sheets from a folding mechanism which consists in causing the sheets to traverse an S shaped path between the folding mechanism and the point of delivery to prevent their assuming a flat condition and cause them to resist the tendency to buckle in the direction of their movement.
2. The method of delivering folded sheets which consists in directing them forwardly, curving the forward ends of the sheets transversely, reversely curving the ends of the sheets while in that condition, carrying them forward, and delivering them.
3. The method of delivering folded sheets, which consists in moving them forward, transversely curving the forward ends of the sheets, continuing the forward motion, but keeping the sheets curved, and thereafter simultaneously retarding the motion of the sheets and curving their ends directly from a curvature in one direction to one in a reverse direction.
4. The method of delivering folded sheets, which consists in moving them forward

folded edge foremost, curving the forward end of the sheets transversely, retarding the motion of the sheets while in such curved condition and simultaneously curving the forward end in a reverse direction, then carrying them forward along the latter curve and delivering them.

5. The method of delivering a bundle of folded sheets which consists in passing them through a pair of delivery rolls, giving the advance end of said bundle of sheets a cross curve, dropping the sheets from the rolls and guiding them to move along to retain said curve, receiving the ends of said sheets and bending said ends in a reverse direction to prevent the ends remaining any appreciable length of time in a flat condition, retarding the speed of the sheets, and delivering them.

6. The method of delivering sheets which consists in giving the advance end of said bundle of sheets a cross curve, guiding them to move along to retain said curve, receiving the ends of said sheets while in said curved condition, preventing the ends remaining any appreciable length of time in a flat condition, and delivering them.

In testimony whereof I have hereunto affixed my signature.

HENRY A. WISE WOOD.
